UNITED STATES PATENT OFFICE.

BARNET NEWLAND, OF NEW YORK, N. Y.

DESIGN FOR A BODY PLATE.

Application filed August 17, 1928. Serial No. 27,856. Term of patent 7 years.

To all whom it may concern:

Be it known that I, BARNET NEWLAND, a citizen of the United States, and residing at New York city, in the county of New York and State of New York, have invented a new, original, and ornamental Design for a Body Plate, of which the following is a specification, reference being had to the accompanying drawings, forming part hereof.

Fig. 1 is a front elevation of the body plate embodying my invention.

Fig. 2 is a side elevation of the body plate embodying my invention.

I claim:

The ornamental design for a body plate as shown.

BARNET NEWLAND.
